UNITED STATES PATENT OFFICE.

EARL R. BROWN, OF REDLANDS, CALIFORNIA.

ORE SEPARATOR.

1,422,736.

Specification of Letters Patent. Patented July 11, 1922.

Application filed March 24, 1921. Serial No. 455,004.

To all whom it may concern:

Be it known that I, EARL R. BROWN, a citizen of the United States, residing at Redlands, in the county of San Bernardino and 5 State of California, have invented new and useful Improvements in Ore Separators, of which the following is a specification.

It is the object of this invention to provide an ore separator adapted for use in 10 placer mining.

The apparatus consists essentially of a fluid receptacle having an ore receptacle mounted therein and open to the fluid receptacle at the center of its base. Agitating 15 means are arranged within the ore receptacle, and the ore is supplied to said receptacle at the periphery of its base so that the whirling motion of the fluid within the ore receptacle will suck the tailings across the 20 riffle provided upon the base of the ore receptacle so as to discharge said tailings into the fluid receptacle while retaining the precious metals separated from the tailings upon the riffle board.

25 The invention will be readily understood from the following description of the accompanying drawings, in which—

Figure 1 is a side elevation of an apparatus, constructed in accordance with the invention, partly broken away.

Fig. 2 is a longitudinal section on the line 2—2 of Fig. 1.

Fig. 3 is a plan view of the apparatus.

Fig. 4 is a transverse section on the line 35 4—4 of Fig. 2.

The outer receptacle of the apparatus is shown as a bucket 1 forming the fluid receptacle and having an annular rim 2 upon its inner surface approximately midway of 40 the height of said receptacle. An annulus 3 is removably received upon this rib and supports a screen 4 depending within receptacle 1 and arranged to collect the tailings from the ore separation. An inner receptacle 5 forming the ore receptacle is removably received within receptacle 1 and is supported upon annulus 3 resting upon rib 2. The walls of receptacle 1 preferably flare 45 upwardly, while the wall of receptacle 5 is substantially cylindrical in order that a space 6 will be provided between receptacles 50 1 and 5.

The base of receptacle 5 is open at its center to the outer receptacle, as shown at 55 8, and the base of the ore receptacle forms a

riffle board. For this purpose a suitable base 9, preferably of wood, is received upon the base of the ore receptacle, and a suitable fabric material, or the like, such as shown at 10, is fixed upon this wooden base. The 60 riffle received upon the surface 10 preferably comprises a spiral rib 12 forming a spiral passageway extending from the periphery of the base of the ore receptacle to the axial opening 8 therein.

At the periphery of axial opening 8 an upward extension is provided upon the base of the ore receptacle and shown at 8^a, said extension being preferably conically disposed and adapted to form a trap for the material 70 flowing through the spiral passageway in order to prevent the discharge of any precious metals through opening 8. In order to further provide for the trapping of all of the metals recovered from the ore, the inner end of the spiral rib is preferably extended as shown at 12^a so as to connect with the next outer convolution of the rib and thereby form a stop extending across the 75 spiral passageway.

The ore to be separated is supplied to the ore receptacle at the periphery of its base, and for this purpose an opening 14 is provided in the side wall of receptacle 5 at its base. This opening communicates with the 80 interior of the ore receptacle adjacent the outer end of the spiral passageway provided by riffle 12, and a baffle plate 15 depending from the wall of the ore receptacle preferably overlies the spiral passageway at 85 opening 14 so as to direct the ore entering the ore receptacle downwardly against the base of the latter. A chute 16 extends upwardly from opening 14 in the space between the outer receptacle and the ore receptacle, 90 said chute being preferably formed as an extension from the wall of receptacle 5.

The liquid level within the apparatus is preferably maintained an appreciable distance above the base of the inner receptacle 100 so that a part of said liquid will be within the inner ore receptacle, and means are provided for causing a whirling motion of the liquid within the ore receptacle so as to create a whirling pool adapted to suck the 105 ore entering through opening 14 radially across the base of the ore receptacle and thence outwardly through the opening 8.

The means provided for creating this 110 whirling motion of the liquid includes a bar

20 extending across the top of receptacle 1 and pivoted thereto at one side as shown at 21 and provided at its swinging edge with a suitable locking means 22. A bearing 5 bracket 23 depends from bar 20 within the receptacle 1, and a shaft 24 is journaled in this bearing bracket and in the bar 20. The lower end of the shaft is threaded and is adapted to receive a transverse paddle bar 10 25 which is fixed to the shaft in adjusted positions lengthwise thereof by nuts 26 threaded onto the shaft above and below the paddle bar. The upper end of the shaft which extends above transverse bar 20 has a 15 pinion 27 fixed thereon, and this pinion meshes with a gear 28 journaled upon the transverse bar 20 and provided with a suitable handle 29 for rotating the same.

In operation, water having been supplied 20 to the apparatus so as to stand at any desired height within ore receptacle 5, the ore to be separated is supplied through chute 16, and the paddle bar 25 is rotated by turning handle 29. As a consequence a whirling 25 pool is created within the ore receptacle, and the ore entering the same will be discharged through opening 8 to the screen 4, while the precious metals separated from the tailings will collect in the passageway provided by 30 the spiral riffle.

When desired the transverse bar 20 may be swung back so as to remove the agitating mechanism from the apparatus, and by then removing the ore receptacle, the screen 4, in 35 which the tailings are collected, may be removed and dumped so that the apparatus is again ready for use without necessitating refilling of the same with water.

Various changes may be made without 40 departing from the spirit of the invention as claimed:

What is claimed is:

1. An ore separator comprising a fluid receptacle, an ore receptacle mounted therein and having an opening in its base to said fluid receptacle, means for creating a whirling motion of the fluid within said ore receptacle, means for supplying ore to the periphery of the base of said ore receptacle, and a spiral riffle upon the base of said ore receptacle forming a spiral passageway for said ore leading to said opening in the ore receptacle.

2. An ore separator comprising a fluid receptacle, an ore receptacle mounted therein and having an opening in its base to said fluid receptacle, means for creating a whirling motion of the fluid within said ore receptacle, means for supplying ore to the periphery of the base of said ore receptacle, a spiral riffle upon the base of said ore receptacle forming a spiral passageway for said ore leading to said opening in the ore receptacle, and trapping means at the end of said passageway adjacent said opening.

3. An ore separator comprising a fluid receptacle, an ore receptacle mounted therein and having an opening in its base to said fluid receptacle, means for creating a whirling motion of the fluid within said ore receptacle, means for supplying ore to the periphery of the base of said ore receptacle, a spiral riffle upon the base of said ore receptacle forming a spiral passageway for said ore leading to said opening in the ore receptacle, and a baffle for directing the ore entering the ore receptacle against the base of the same.

In testimony whereof I have signed my name to this specification.

EARL R. BROWN.
